(57) **CLAIM**

The ornamental design for a seat for an automobile, as shown and described herein.

DESCRIPTION

FIG. 1 is a front side perspective view of a seat for an automobile.

FIG. 2 is a rear side perspective view of a seat for an automobile.

FIG. 3 is a front view of a seat for an automobile.

FIG. 4 is a rear view of a seat for an automobile.

FIG. 5 is a top plan view of a seat for an automobile.

FIG. 6 is a right side view of a seat for an automobile; and, FIG. 7 is a left side view of a seat for an automobile.

The broken lines in the drawings illustrate portions of the seat for an automobile that form no part of the claimed design.
